Corporation, Toledo, Ohio, a corporation of
Delaware

Application August 2, 1935, Serial No. 34,398

10 Claims. (Cl. 15—13)

This invention relates to vacuum cleaner of the type which agitates an air cushion suspended carpet by means of a high speed motor driven rotary agitator including flexibly mounted beaters, such as that covered in pending application Serial No. 752,270, filed November 9, 1934, of which the present application constitutes a continuation in part.

The object of this invention is to provide a rotary agitator which reduces carpet injury to a minimum while preserving a maximum of dirt loosening efficiency. The invention achieves this aim by providing an agitator with a beater element so mounted as to have a high circumferential yieldability relative to a low radial yieldability and a low radial distensibility (radial stability).

The invention involves the discovery that the primary factor in reducing carpet injury, is circumferential yieldability, while the important factor in preserving dirt loosening effectiveness, is radial stability. Circumferential yieldability greatly reduces the "drag" against the pile fibers, but does not materially lessen the effectiveness of the blow struck by a radially stable beater element. The vertical punch of the blow has little injurious effect, but does knock the dirt loose. Accordingly, the invention aims to reduce the "side swiping" effect of the beater element to a minimum, while preserving vertical punching effectiveness and constraining the beater element to travel within a narrow limit of distension beyond a fixed path of revolution of its carpet contacting surface. The latter is important for the reason that the agitator is very sensitive to slight changes in the adjustment of the height, in the nozzle, of its beater element at contacting position.

The invention of course also contemplates the use of means to resiliently urge the beater element toward a definite initial striking position, and to return it to that position after it has been deflected therefrom by a carpet blow, with sufficient quickness so that such return movement will be encompassed within less than 360 degrees of revolution of a high speed motor driven agitator.

In the accomplishment of the foregoing objects, the invention provides a rotating spindle and a rigid beater element, elongated parallel to the axis of the spindle, and connected to the spindle by a hinge located approximately at the surface of the spindle and at one side of the neck of the beater element, allowing the other side of said neck to be displaced from its normal

position relative to the spindle as the beater element swings circumferentially, and means resiliently urging said other side back to normal position after it has been deflected therefrom by a carpet blow. The hinge is such as to prevent direct radial depression of the beater element, constraining its carpet contacting region to swing at constant distance from the hinge axis. In one form of the invention the distance of the contacting surface from the spindle axis increases slightly as the beater element is deflected, thus augmenting the blow in a radial direction, while in another form, in order to secure a milder beating action the distance between the carpet contacting surface and the spindle axis slightly diminishes during deflection, radial non-yieldability being present, however, in any given position of deflection.

With these and other objects in view the invention consists in the combination and construction and arrangement of the various parts thereof, whereby the objects contemplated are attained, as more fully set forth in the accompanying specifications, pointed out in the claims, and illustrated in the accompanying drawings, in which:

Fig. 16 is a similar view of a modification thereof.

Fig. 17 is a similar view of a modification thereof.

5 Fig. 18 is a similar view of a modification thereof.

Referring now to Fig. 1, the invention is embodied in a vacuum cleaner having a suction neck 10 to which is swivelled the floor tool 11. In the 10 suction chamber 12 of the latter is journalled the rotating spindle 13 carrying detachable brush elements 14 and beaters 15. A belt 16, driven by a motor 17, transmits high speed rotation to the spindle 13. The suction chamber 12 is carried at 15 a height above the supporting surface, by wheels 18, and the suction mechanism (not shown) attached to neck 10, lifts the carpet 19 against the mouth of the chamber 12, whence the carpet is beaten and brushed by beaters 15 and 20 brushes 14.

Each beater 15 comprises an elongated channel 20 (Fig. 2) of rigid material such as metal having a semicylindrical carpet engaging region 21 connecting the side walls 22 which are preferably 25 drawn toward each other so as to provide a reduced neck region. In the form shown in Fig. 2, the channel 20 embraces one side of a strip of soft rubber 23 to which it is secured either by bonding or by the engagement of the reduced 30 neck of the channel with the reduced neck of the rubber strip. The other side of the strip is secured, by bonding, in an elongated channel 24 which in turn is mounted in a socket formed in the spindle 13, and secured by some suitable 35 releasable securing means, such as the set screws 25.

The agitator revolves as indicated by the arrow 26, and as the beater contacts the carpet, it swings around a hinge 29 formed by engagement 40 of the edge of the trailing side wall 22 against the registering edge of one side of the channel 24, or against the surface of the spindle 13 in case the channel 24 is dispensed with.

As the beater swings in this manner, its carpet 45 engaging face 21 will describe, relative to the hinge axis, a path indicated by the broken line 46, moving slightly downwardly relative to the level of the path 46 which it would describe if fixed rigidly to the spindle. In Fig. 2 it is shown at 50 approximately the bottom of its swing. This increases the radial "punching" action of the beater, while the circumferential deflection slows up circumferential movement and decreases the injurious "swiping" action against the carpet. 55 Theoretically, it would be possible to adjust the resiliency of the mounting, and the weight of the beater so that circumferential movement of the beater would practically come to a standstill while the spindle continued to revolve above it, 60 the resulting movement of the carpet engaging face 21 being virtually a simple vertical reciprocation. In practice, however, it is not necessary to approach this limit, the face 21 being rounded in a broad curve and being smooth, hard, and 65 highly polished so as to slide over the pile with ease. The invention does, nevertheless, effect a very substantial reduction in the very real pile removing whipping action which characterizes a rigidly mounted beater.

70 After severing contact with the rug, the beater will be pulled back to the normal position which is illustrated at the top of Fig. 2, wherein the edges of both walls 22 of the beater channel are in contact or substantial contact with the channel 75 24 or the spindle.

One advantage of this particular construction is the complete covering of the side faces of the rubber by the metal beater channel when the beater is in normal position, so as to eliminate the deteriorating effects of air in contact with the 5 rubber.

In the form shown in Fig. 4, a thin bead 27 of rubber projects between the abutting edges of the channels 20 and 24 so as to eliminate any noise occurring from contact of the metal edges 10 against each other. The hinging action in this case is practically the same as in the form shown in Fig. 2.

The resiliency of the mounting may be increased by leaving the rubber unattached to the 15 interior for a considerable distance from the upper edge downwardly of the leading wall of the channel, as indicated at 28 in Figs. 4 and 5. Preferably this feature would include a slight spacing between the rubber and the metal so as 20 to avoid frictional contact. The greatly increased area of rubber which may freely stretch in order to allow the beater to hinge, gives a much freer flexing action than is true of the 25 form shown in Fig. 2.

In the form of the invention shown in Fig. 5, a conventional hinge 29 connects the trailing wall 22 with the channel 24 and rigidly prevents any radial distension of the beater under 30 centrifugal force.

In the form shown in Fig. 6, that portion of the leading wall 22 which is unattached to the rubber, has been cut away as at 28a, leaving the opposite or trailing wall hinged to the channel 24 as heretofore described.

In the form shown in Fig. 7, the beater has been lightened by leaving its carpet engaging region 21 empty and forming its neck region 22a to engage a flattened, radially short body of rubber 23a mounted in a channel 24 as in the forms 40 hereinbefore described. The hinge is formed in the same manner as in Fig. 4.

In the form shown in Fig. 8, the beater 20 is hinged at 29 to one edge of a plate of spring metal 30 which is secured to the spindle by securing 45 elements 31 positioned close to the hinge 29. The other end of the spring plate 30 projects freely into a cavity 32 in the spindle and is engaged by a flange 33 on the other side of the beater 20. The spring plate 30 forms the means for resiliently returning the beater to normal position and allowing it to be deflected circumferentially around the hinge 29.

In Fig. 9, the beater 20 is hinged at 29 to the spindle 13, and is resiliently urged towards normal position by coil spring 34 one end of which is attached to the spindle as at 35 and the other end of which is attached as at 36 to the beater 20. Most of the length of the coil spring is accommodated in the hollow interior of the beater 60 20. A buffer block 37 is mounted in the spindle 13 to receive the impact of the leading wall of the beater when it has been pulled back to normal position.

In all of the Figs. 2-9 inclusive, with the exception of Fig. 8, the beater is shown in deflected position. In normal position, as shown in Fig. 8, the medial plane of the beater is located along a radius of the spindle 13.

In each case, the agitator rotates in the direction indicated by the arrow 26.

In the form shown in Figs. 10 to 18 inclusive, the leading wall of the metal channel-shaped beater is hinged as at 38 to the spindle 13, while the trailing wall engages a compressible means 75

- which allows the beater element to be depressed while hinging laterally and which returns the beater element to normal position upon severance of carpet contact. In Fig. 10, the compressible means is a coil spring 39 socketed in a recess 40 in the spindle. If one spring is used it is positioned midway between the ends of the beater. If two are used they are positioned near the respective ends of the beater.
- 10 In the form shown in Fig. 11, the compression means is a strip of rubber 41 socketed in a depression 42 in the spindle 13, and which engages the edge of the trailing wall 22 of the beater.
- 15 In the form shown in Fig. 12, the compression means is a body of rubber 43 which fills the beater and the mounting channel 24a to which the beater is hinged. The edge of the trailing wall of the beater in this case does not register 20 with the corresponding wall of the channel 24a, but is positioned somewhat inside of the plane of the channel wall so that it can move up into the channel 24a. The rubber 43 is detached from the channel 24a at that side so that during 25 compression it may have freedom of movement to pull away from the channel as at 44.
- In the forms shown in Figs. 10, 11, and 12, there is an actual hinge 38 between the leading wall 22 of the beater and the spindle 13. In the 30 form shown in Fig. 13, the hinge is formed by abutting contact of the edge of the leading wall 22 with the edge of the channel 24a which in this case, as in Fig. 12, is somewhat wider than the neck 22 so as to allow the trailing wall 35 to move into the channel.
- In the form shown in Figs. 15 and 16 the trailing wall 22 is cut away as at 26b and compression occurs in the region of rubber thus exposed.
- In Fig. 15 the hinge is formed by abutting 40 contact, as in Fig. 13, while in Fig. 16 the metal hinge 38 is employed. In Fig. 17 the beater 20 is hinged at 38 to the spindle 13 and its trailing wall 22 engages a resilient plate or leaf spring 35a which forms the compression means. A depression 32a in the spindle allows the trailing side 45 of the beater to move up into the spindle as it swings around the hinge 38.
- In the form shown in Fig. 18, a leaf spring 35b not only serves as the means for resiliently 50 opposing deflection and for returning the beater to normal position, but also as the hinge between the leading side of the beater and the spindle 13. A depression 32b allows the trailing side of the beater to move up into the spindle during 55 deflection.
- In place of the leaf spring 35b, there may be employed a resilient extension 35c of the leading wall 22 of the beater, secured at 55 to the spindle. In the forms of the invention shown in Figs. 14 60 and 18 a buffer block 37a may be employed to receive the contact of the trailing edge of the beater.
- Each of the forms shown in Figs. 10, 11, 12, 13, 14, 17, and 18 embody the advantage of having 65 the beater extend entirely to the periphery of the spindle. This not only improves appearance but increases the durability of the device as a whole and protects the resilient cushioning mechanism encased within the hollow beater.
- 70 While there is a slight radial recession of the beater towards the axis of the spindle during carpet contact, in those forms shown in Figs. 10 to 18, this recession can occur only as an incident to the circumferential swinging of the beater, and 75 is proportional thereto and only a small incre-
- ment thereof. As a consequence, a blow is delivered which, though cushioned by circumferential flexing, is nevertheless positive in a radial direction and gives an effective beating action. It differs from the blow given by the forms shown 5 in Figs. 1 to 9 inclusive in that in the former, the blow slightly increases in intensity during the initial period of carpet contact whereas in the forms shown in Figs. 10 to 18 inclusive, the blow slightly decreases in intensity during carpet contact.
- An important aspect of the invention is the dimensioning of the parts so that the beater projects radially beyond the spindle a distance approximately as much as the radius of the spindle, and the locating of the active portion of the resilient means close to the periphery of the spindle and close to the hinge which is located at the periphery, so that resistance to circumferential flexing is minimized, the lever arm from 20 the region of contact to the hinge being definitely longer than that from the hinge to the region of resilient opposition to circumferential flexing.
- Another important phase of the invention is the use of an elongated beater attached to the 25 spindle along an extended hinge, which allows the beater, in retreating from the blow of the carpet, to yield only in one direction—circumferentially. This ensures the injection of the 30 full force of the rotating spindle into the downward blow delivered by the beater.
- Another important feature of the invention, is the attachment of the beater, to the spindle on a fixed axis hinge, i. e., a hinge the axis of which is 35 practically immovable radially of the spindle, and one in which there is no play such as would allow the beater to swing in an extended path when free of the carpet, and then recede radially toward the axis of rotation when the carpet is struck. The rubber, in Figs. 2, 4, 7, 13, and 15, is 40 of sufficient thickness and strength at the region of junction between beater and spindle, to hold the beater within a path which is practically non-distensible at any speed of rotation, and abutting contact of walls 22 and channel 24 or spindle, 45 prevents radial recession. In the other form, the same results are furnished by the actual hinge 29.
- We claim as our invention:
1. In a vacuum cleaner, a rotating spindle, a rigid beater hinged thereto on an axis parallel to the axis of rotation and projecting radially from the hinge a distance not substantially less than the radius of the spindle, so as to be capable of receding under carpet contact with a recession 55 that is predominantly circumferential, and resilient means for urging said beater toward a radial position and for resisting such recession.
  2. In a vacuum cleaner, a power driven rotating spindle, and a rigid beater projecting radially 60 therefrom, the extremity of one side of which is hinged to the spindle to allow the beater to swing circumferentially of the spindle, and resilient means attaching the other side of the beater to the spindle so as to allow the beater to recede 65 under carpet contact and to return it to normal position upon severance of carpet contact the radial distance from the hinge to the path of revolution of the carpet contacting tip being substantially greater than the circumferential distance from the hinge to the radius on which said tip is normally located, whereby the circumferential component of the deflection of said tip is materially greater than the radial component 70 thereof.

3. In a vacuum cleaner, a power driven rotating spindle, and a beater attached thereto and projecting radially therefrom, said beater comprising an elongated channel of rigid tough wear resisting material, the extremity of one side of which is hinged to the spindle to allow the beater to swing circumferentially of the spindle, and resilient means attaching the other side of the channel to the spindle so as to allow the beater to recede under carpet contact and to return it to normal position upon severance of carpet contact, the radial distance from the hinge to the path of revolution of the carpet contacting tip being substantially greater than the circumferential distance from the hinge to the radius on which said tip is normally located, whereby the circumferential component of the deflection of said tip is materially greater than the radial component thereof.
4. In a vacuum cleaner, a power driven rotating spindle, and a rigid beater projecting radially therefrom and attached thereto on a hinge which is elongated parallel to the axis of rotation and radially immovable relative to said axis, so as to hold the adjacent region of the beater against either extension or depression radially, said hinge being located at one side of the beater, and resilient means attaching the other side of the beater to the spindle so as to allow the beater to freely recede circumferentially of the spindle under carpet contact, and to return it to normal position upon severance of carpet contact, the radial distance from the hinge to the path of revolution of the carpet contacting tip being greater than the circumferential distance from the hinge to the radius on which said tip is normally located, and greater than the distance from the hinge to the region of action of the resilient means.
5. In a vacuum cleaner, a power driven rotating spindle; and a rigid beater projecting radially therefrom and attached thereto on a hinge which is elongated parallel to the axis of rotation and radially immovable relative to said axis, so as to hold the adjacent region of the beater against either extension or depression radially, said hinge being located at one side of the beater, and resilient means attaching the other side of the beater to the spindle so as to allow the beater to freely recede under carpet contact, and to return it to normal position upon severance of carpet contact, the radial distance from the hinge to the path of revolution of the carpet contacting tip being substantially greater than the circumferential distance from the hinge to the radius on which said tip is normally located, whereby the circumferential component of the deflection of said tip is materially greater than the radial component thereof.
6. In a vacuum cleaner, a power driven rotating spindle, and a beater attached thereto and projecting radially therefrom, said beater comprising an elongated channel of rigid tough wear resisting material, the extremity of one side wall of which is attached to the spindle on a hinge which is parallel to and radially immovable relative to the axis of rotation, so as to hold the adjacent region of the channel against either extension or depression radially, and resilient means attaching the other side of the channel to the spindle so as to allow the beater to freely recede circumferentially of the spindle under carpet contact and to return it to normal position upon severance of carpet contact, said resilient means being located within the channel.
7. In a vacuum cleaner, a rotating spindle, a beater hinged thereto, comprising a channel of rigid material, and resilient means extending into the channel and attached thereto, for yieldingly maintaining said channel in a normal position and allowing the same to recede circumferentially of the spindle under carpet contact while yieldingly resisting such recession, one side wall of said channel extending substantially to the periphery of the spindle and the edge of the other side wall being spaced from the spindle so as to leave an exposed area of the resilient means and to thereby facilitate flexing.
8. In a vacuum cleaner, a rotating spindle, a beater projecting therefrom in substantially a radial direction to a distance substantially as great as the radius of the spindle, and attached thereto for circumferential deflection on an axis parallel to the axis of revolution of the spindle, the axis of deflection being located, relative to the direction of rotation, a distance rearwardly of a radius passing through the center of the spindle and the carpet contacting tip when the beater is undeflected, which distance is substantially less than the radial distance of the carpet contacting tip from the spindle, whereby the latter distance will be increased during the initial stage of recession and whereby the deflection will be predominantly circumferential in direction.
9. In a vacuum cleaner, a rotating spindle, a rigid beater projecting therefrom in substantially a radial direction to a distance substantially as great as the radius of the spindle, and hinged thereto for circumferential deflection on an axis parallel to the axis of revolution of the spindle, the axis of deflection being located, relative to the direction of rotation, a distance rearwardly of a radius passing through the center of the spindle and the carpet contacting tip when the beater is undeflected, which distance is substantially less than the radial distance of the carpet contacting tip from the spindle, whereby the latter distance will be increased during the initial stage of recession and whereby the deflection will be predominantly circumferential in direction.
10. In a vacuum cleaner, a power driven rotating spindle, and a rigid beater projecting radially therefrom and attached thereto on a hinge which is elongated parallel to the axis of rotation and radially immovable relative to said axis, so as to hold the adjacent region of the beater against either extension or depression radially, said hinge being located at one side of the beater, and resilient means attaching the other side of the beater to the spindle so as to allow the beater to freely recede circumferentially of the spindle under carpet contact, and to return it to normal position upon severance of carpet contact, the hinge being related to the direction of rotation so that the carpet contacting tip of the beater will be forced to increase its radial distance from the axis of rotation during the initial stage of the circumferential recession.
